UNITED STATES PATENT OFFICE.

JACOB HEILBRON, OF PROVIDENCE, RHODE ISLAND, ASSIGNOR, BY MESNE ASSIGNMENTS, TO IDA GOLDRING, OF PROVIDENCE, RHODE ISLAND.

POWDER CONTAINER.

Application filed June 9, 1925. Serial No. 35,938.

My invention relates to powder containers, more especially to vanity cases and comprises improved means for dispensing powder therein. This application is a continuation in part of my earlier application S. N. 732,949 filed August 19, 1924, and a continuation in part of my earlier application S. N. 755,060 filed December 10, 1924.

The main object of my invention is to provide in a powder container improved means for dispensing of powder. My invention is particularly adapted for use in vanity cases. Powder in powder form is preferred by most users as the user can purchase her own special brand of powder which she usually prefers to the unknown constituents of a compact. So far as I am aware, no satisfactory means has heretofore been provided for properly dispensing powder in a vanity case and insuring against leakage.

I am aware that compartment cover members in vanity cases have been provided with slits through which powder may be fed on to a dispensing surface on the top thereof on shaking of the box while held in a horizontal position. I am also aware that a vanity case has been provided wherein powder has been fed laterally on to a dispensing surface comprising one of the cover members. I am also aware that compartment covers having a plurality of holes and cooperating shutter members or resilient spring members underneath to force the powder through on pressing down thereof have been provided. The chief drawback of all these constructions has been the amount of loose powder always present.

The essential feature of my invention is to provide in a powder container a member having a dispensing surface which in a vanity case is preferably the main body portion of the case and a cover member having a hole therein spaced from said dispensing surface, said members forming between them a compartment to receive the powder. In my preferred embodiment, the dispensing surface is circular as is the hole in the cover member. Said dispensing surface and cover members may be so spaced as to readily admit the desired amount of powder to the dispensing surface on the shaking of the box.

A further object of my invention is to provide in the type of container described in the previous paragraph, improved means to reg-

ulate the amount of material fed to the dispensing surface. I accomplish this by providing means to vary the distance between the hole and the dispensing surface. To vary at the user's pleasure the amount of powder fed thereto, though any means for varying the distance between said hole and dispensing surface may be provided I preferably provide a revolvable compartment cover member threadedly engaged with a pocket in the casing body member whereby on revolution thereof the distance between said hole and dispensing surface may be varied. It is obvious that said container may be adjusted so that the edge of the hole will contact the cooperating dispensing surface, when as is apparent, it becomes impossible for powder to flow from the compartment on to the dispensing surface, an ideal condition for travel.

A further object of my invention therefore is to provide improved means to lock the powder within a compartment provided therefor when the container is not in use. So far as I am aware no suitable means have heretofore been provided for this purpose.

A further object of my invention is to provide improved means for filling the powder compartment. It is obvious that on the further raising up of the cover member, powder may be inserted into said compartment through the annular space then formed between said hole in the cover member and said dispensing surface. At times to fill the powder compartment, it is desirable to separate the body portion from the compartment cover member. To this end I have provided grooves extending from approximately the bottom of the angularly disposed grooves in the side wall of the cover member to the bottom thereof.

Especially in a vanity case a saucer shaped dispensing surface is desirable. Therefore, in my preferred embodiment I preferably taper or incline the upper annular portion of the cover member exterior of said hole from the outer edge to the hole whereby said annular portion may cooperate with the dispensing surface of the body member underneath said hole to form a complete saucer shaped powder dispensing surface on which the usual puff may be readily filled by the user.

A further object of my invention is to pro-

vide improved means to prevent leakage of powder in this type of case. To prevent leakage between the hole and dispensing surface, in my preferred embodiment, I terminate the hole in the compartment cover member preferably in a bevelled edge and I preferably surround the dispensing surface of the body member with an upwardly projecting ridge. As the cover member is 5 adjustably moved from a position to feed powder to the dispensing surface to a position to cause the edge of the hole to register against the dispensing surface, it is obvious that a ring of powder will be compactly retained between the lower side of the cover member and said upwardly projecting ridge, this layer of compressed powder preventing 10 leakage of powder between said hole and dispensing surface and forming an hermetic seal to keep the powder in its original 15 freshness and fragrance. In my preferred embodiment I preferably more sharply taper the lower portion of the inclined dispensing surface of the compartment cover member so 20 that it may more readily form said powder sealing ring. Though in my preferred embodiment I have shown the edge of the hole of the compartment cover member and the upwardly projecting ridge surrounding the 25 dispensing surface on the body member as the preferred means to form this powder seal it is obvious that any suitable type of means on the compartment cover member adapted to cooperate with any suitable type 30 of means adjacent to the dispensing surface on the body member may be provided to accomplish this result.

To prevent leakage of powder between the relatively movable sides of the compartment 40 cover member and the sides of the pocket in the body member I have provided the downwardly extending grooves in the sides of the cover member hereinbefore referred to with dam portions of lesser depth thereby tending 45 to prevent leakage of powder through said grooves and practically eliminating leakage of powder at these points. These dam portions have an additional function. As they are placed substantially adjacent to the bottom of the angularly disposed 50 grooves, in order to separate said compartment cover and body members it is necessary to exert a comparatively large vertical force to raise the inwardly projecting lugs 55 of the body member over said dam portions.

To further prevent leakage of powder and to provide means whereby the edge of the compartment cover member may be more readily grasped for moving it relatively to 60 the body member I have provided said compartment cover member with a radially projecting bead on the upper portion of the side wall thereof which normally at all times remains above said body member. When said compartment cover member is relatively

lowered to its lowest portion it is obvious that the lower edge of said bead will contact the upper edge of the side wall of the body member thereby forming a seal to prevent leakage of powder at this point.

Though any means resilient or otherwise may be provided to raise up the hole in the cover member from the dispensing surface to accomplish these results it is obvious that by providing a revolvable compartment 70 cover member threadedly engaged with the body member as shown in my preferred embodiment improved means are provided for this purpose whereby the distance between the hole and the dispensing surface may be varied on mere revolution of the compartment cover member.

A vanity case, in addition, is usually provided with an external cover member hinged to the body member thereof. By having the compartment cover member of a greater height than the body portion, thereby permitting the external cover member to telescope over the compartment cover member above said bead where employed, I provide means to lock said external cover member to said compartment cover member when said compartment cover member is in any special position, in my preferred embodiment, preferably when the edge of the hole in the compartment cover member and the dispensing surface contact thereby securely locking the powder within the compartment, and thereby only permitting locking of said external cover member when the compartment is locked and preventing its locking at other times. For this purpose I preferably provide cooperating latch portions on the side wall of the external cover member and on the upper side wall of the compartment 95 cover member to engage to lock said portions together when the compartment cover member is moved to the aforesaid predetermined position.

To permit the external cover member to 110 be conveniently hinged to said body member, I preferably omit a portion of the bead radially projecting from the upper surface of the side wall of the compartment cover member adjacent to said hinge. It is obvious 115 that in order for the latch portion on the compartment cover member to come into proper alignment with the complementary latch portion on the external cover member to perform the function mentioned in the just preceding paragraph, said compartment and cover members must be detachably secured together by inserting the proper lugs in the proper grooves. The fact that the bead is omitted adjacent to the hinge thus 120 indicates to the user the proper lugs to insert into the proper grooves to have the complementary latch portions heretofore referred to brought into proper alignment in use to 125 accomplish this result.

These and such other objects of my invention as may hereinafter appear will be best understood from a description of embodiments thereof such as those shown in the accompanying drawings.

In the drawings, Fig. 1 is a perspective view of the preferred form of a vanity case employing my invention.

Fig. 2 is a plan view of said case with the external cover member broken away and powder puff removed.

Fig. 3 is a cross sectional view of a vanity case employing my invention with the powder compartment cover member locked and the external cover member also locked.

Fig. 4 is a cross sectional view similar to Fig. 3 with the compartment cover member partly revolved to permit the feeding of a predetermined amount of powder on to the dispensing surface.

Fig. 5 is a cross sectional view of the compartment cover member and body member of my invention just as said members have been separated to permit insertion of powder into the compartment.

Fig. 6 is a perspective view of the compartment cover member.

Fig. 7 is a perspective view of the body member.

Fig. 8 is a side elevation of the compartment cover member.

Fig. 9 is a detailed sectional view of a portion of the side of the case showing the complementary latch means I employ to lock the external cover member to the compartment cover member and the cooperating lugs and grooves to permit relative revolution of said members.

Fig. 10 is a fragmentary view showing the powder seal formed between the lower edge of the top surface of the compartment cover member and the cooperating projecting ridge in the body member.

Fig. 11-16 are views of a modified form of my invention wherein a different type of means to vary the distance between the body and compartment cover members is employed.

Fig. 11 is a plan view of said modified case with the external cover member broken away, powder puff removed and a portion of the top of the compartment cover member broken away.

Fig. 12 is a side elevation of the compartment cover member provided with the inverted L shaped depressions of this type.

Fig. 13 is a cross sectional view showing the hole in the compartment cover member registering against the dispensing surface of the body member thereby locking the powder compartment and with the external cover member also locked.

Fig. 14 is a cross sectional view similar to Fig. 13 with the compartment cover member forced by the resilient means employed

in this embodiment away from the dispensing surface to permit feeding of powder to the dispensing surface.

Fig. 15 is a perspective view of the resilient means employed.

Fig. 16 is a detailed sectional view of the portion of the side of the case.

In the drawings, wherein like characters of reference indicate like parts throughout, 20 generally indicates a vanity case constructed in accordance with my invention. 22 indicates the body portion thereof which as shown in my preferred embodiment is preferably of cylindrical shape having the side walls 24 projecting upwardly from the base 26 thereof.

While any portion of any member of the container may be used as the dispensing surface, in my preferred embodiment I employ as the main dispensing surface the central circular body portion 28 of the body portion 22.

The compartment cover member 30 is adapted to enclose the annular portion of the container containing the dispensing surface 28 exterior of said surface which in my preferred embodiment is the body portion 22 and is provided with the hole 32 substantially coincident with and in my preferred embodiment over the dispensing surface 28. In my preferred embodiment said hole 32 is preferably circular. Said compartment cover member 30 is also provided with side walls 34 and has the upper wall 36 covering the portion of the body portion not included in the dispensing surface 28.

It is obvious that the compartment 40 is formed between the side walls 24 and base 26 of the body member 22 and cover portion 36 of the compartment cover member 30 adapted to contain powder 42.

In the preferred embodiment of the vanity case shown, to more readily aid in dispensing of the powder 42, I form the upper wall 36 of the compartment cover member into the additional dispensing surface 36 and I preferably taper said surface from the side 34 of said compartment cover member 30 downwards towards the hole 32. The powder puff 44 having the usual tab 46 thereon for raising it up conveniently rests on top of the compartment cover member on the dispensing surface 36 thereof and the dispensing surface 28 of the body member 22. It is obvious that I have taken a construction common in vanity cases of two dispensing surface the outer preferably annular one 36 normally employed on the usual powder compartment cover member 30 and the inner preferably circular dispensing surface 28 usually employed on the body member 22 and that by forming a hole 32 in the compartment cover member 30 and spacing said hole from the dispensing surface 28 I have

provided improved means for regulating the feed of powder.

In addition to spacing the compartment cover member 30 from the dispensing surface 28 of the body member, I provide means to vary the distance between said members, thus in my preferred embodiment the distance between the hole 32 and dispensing surface 28 to accomplish the results about to be described. While any means to vary the distance between the edge of the hole 32 and the dispensing surface 28 may be employed, I preferably accomplish this by forming a cylindrical pocket in the body member 22 which in my preferred embodiment comprises the entire space enclosed between the wall 24 and the base 26 thereof and I shape the compartment cover member 30 in cylindrical form and of a size to be compactly contained within said pocket of the body member 22. To more accurately adjustably vary the distance between said dispensing surface 28 and the edge of said hole 32 I provide the side walls 24 of said body member 22 with the threads or lugs 50 projecting radially inwardly therein, and to cooperate with said lugs 50 I provide on the side walls 34 of the cylindrical revolvable compartment cover member 30 the cooperating threads or depressions 52 preferably angularly disposed relative to the base 26 of said body member. I provide grooves 53 projecting generally downwardly from preferably the lowest portions of said angularly disposed inwardly projecting grooves 52 to permit the lugs 50 to be drawn downwardly therethrough when it is desired to separate said members for refilling or cleaning purposes. For powder sealing purposes, and to prevent the tendency of said members to separate when said lugs are brought opposite said vertical grooves 53, I preferably provide said vertical grooves 53 with the dam portions 54 of lesser depth therein. It is thus obvious that to separate said members when said lugs 50 are brought opposite the vertically extending grooves 53 it is necessary to exert a substantial force to raise said lugs 50 over said dam portions 54. I also provide further means to prevent leakage of powder. I preferably provide an upwardly projecting ridge 29 on the base 26 of the body member 22 preferably immediately surrounding the dispensing surface 28, I also more sharply taper the inclined cover portion 36 of the compartment cover member 30 adjacent to said ridge as at 33 to cooperate with said ridge 29 to prevent leakage of powder. It is obvious that the dispensing surface 28 and the lower edge of the downwardly tapered upper wall 36 of the compartment cover member cooperate to form a spout 37 preferably annular as in my preferred embodiment converging towards the dispensing surface 28. It is obvious

however, that said spout may be formed in any suitable fashion rather than in the manner shown. The upwardly projecting annular ridge 29 cooperates to form with the lower portion 33 of the upper wall 36 of the compartment cover member a powder seal 43 see Figs. 3 and 10. After a sufficient amount of powder has been shaken on to the dispensing surface in use, it is obvious that some powder will be left adjacent to the surrounding ridge 29. As the lower edge 33 of the top wall 36 of the compartment cover member 30 is brought into close proximity to the upwardly projecting ridge 29 a layer of powder will be compressed between said wall 36 and ridge 29 thereby forming a compressed hermetic powder seal to prevent sifting of the powder from the powder compartment 40 through the spout 37 and to keep the powder in its original freshness and fragrance.

The operation of my invention is obvious from the above description. Fig. 3 illustrates the cylindrical compartment cover member 30 revolved to have the edge of the hole 32 thereof contacting the dispensing surface 28 on the body member. It is thus obvious that it is then impossible for any powder to flow from the compartment 40 on to the dispensing surface 28 or for any powder to leak through the powder seal 43 as just explained if the box has once been used.

Fig. 4 illustrates the compartment cover member 30 revolved on the threads 50 and 52 to space the hole 32 in the compartment cover member 30 at predetermined amounts from the dispensing surface 28 whereby powder may flow radially on the surface 28 through the annular spout 37 as shown at 43 when the vanity case is held in a horizontal position and shaken.

Fig. 5 illustrates the position of the compartment cover member 30 just after it has been separated from the body member 22 by withdrawing of the lugs 50 through the downwardly extending grooves 53 connected to the grooves 52 over the dam portions 54 as explained.

The vanity case 20 is also provided with the external cover member 55 suitably hinged to the body portion 22 as at 56. I provide improved means to prevent locking of the external cover member except when the compartment 40 is locked, said means permitting locking of said external cover member 55 to said container only when said compartment is locked. To accomplish this, in my preferred embodiment I construct the side walls of the compartment cover member 30 of greater height than the side walls 24 of the body member 22. At a predetermined point on the outer periphery of the portion of the side walls 34 of the compartment cover member 30, I provide the latch means which in my preferred embodiment

- preferably comprises the lug 58 thereon and I provide the complementary latch means, in my preferred embodiment comprising the depression 60 on the external cover member 55 preferably diametrically opposite said hinge 56 adapted to receive said lug 50. The lug 58 is preferably so spaced that it will be adjacent to the depression 60 on the external cover member 55 when the compartment 40 cover member 30 is revolved to its lower-most position as shown in Fig. 3 with the edge of the hole 32 registering against the dispensing surface 28, thereby locking the powder 42 within the compartment 40. When in this position it is obvious that on closing the external cover member 55, the lug 58 will register in the depression 60 thereby locking the case. It is obvious that when the lug 58 is in any other position on the periphery of said compartment cover member 30 that it will not register in the depression 60 on closing the external cover member 55 to lock the box. While I have shown the lug 58 and depression 60 as my improved complementary latch locking means, any suitable locking means may be employed. It is thus obvious that I have provided this improved safety means to prevent spilling of powder during travel. So far as I am aware means to lock the powder container only when the powder compartment is locked is new in all types of powder containers and it is obvious that this feature of my invention may be employed where powder is dispensed from the compartment in other manners than shown herein.
- For gripping and powder sealing purposes I preferably provide on the upper portion of the side walls 34 of the compartment cover member the radially projecting bead 70 which bead may be knurled as at 72 if desired. This bead 70 is preferably so situated on the compartment cover member 30 that when said member is moved to a position to cause the edge of the hole 32 to contact the dispensing surface 28 to lock the powder compartment, 40 the lower edge of said bead 70 will abut the upper edge of the side wall 24 of the body member to form a seal at this point to prevent leakage of powder. It is also obvious that the bead provides means whereby the compartment cover member may be readily gripped by the user to move or revolve it as desired. As is shown in Fig. 3 said bead normally separates the side wall of the external cover member 55 from the side wall 24 of the body member.
- I preferably omit a portion of said bead 70 as at 74 adjacent the hinge 56. It is obvious that by doing this I can hinge the external cover member 54 directly to the body member 22 without causing the bead 70 to get in the way of the hinge as used. As explained, I provide a plurality of lugs 50
- adapted to be engaged with a plurality of grooves 53 and 52. It is obvious that unless the proper lugs 50 are engaged in the proper grooves 52 and 53, that the locking lug 58 on the compartment cover member will not be in the correct position to engage the depression 60 on the external cover member 53 when the compartment cover member 30 is moved to lock the compartment. The broken away portion 74 of the bead 70 thus provides an indication whereby the proper lugs 50 may be inserted in the proper grooves 52 and 53 to bring the latch portion 58 on the compartment cover member in alignment with the latch portion 60 on the external cover member to permit locking of the external cover member to the compartment cover member only when the powder compartment is locked.
- In Figs. 11-16 I have shown a vanity case employing a modified form of means to space the hole 32 from the dispensing surface 28. The outer side of the wall 34 of the compartment cover member is provided with the inverted L shaped depressions 52' and the inner side of the wall 24 of the body portion 22 is provided with the usual inwardly projecting lugs 50'. The springs 62 having the bent over portions 64 adapted to engage the upper wall 36 of the compartment cover member 30 and the base 66 adapted to engage the base 26 of the body portion 22 are also provided. When said springs 62 are inserted in position, it is obvious that when the cover member 30 is revolved, the lugs 50' are moved over in the horizontal portions 68 of the inverted L shaped depression 52' until they come opposite the vertical portions 69 thereof when the springs 62 will force the cover member 30 upwards to space the hole 32 the desired predetermined amount from the dispensing surface 28 as shown in Fig. 14. To again lock the compartment 40 push down on the compartment cover member 30 against the springs 62 until the lugs 50 are in the horizontal portions of the inverted L shaped grooves 52' when on rotation of the cover 30 the lugs 50' will be pressed by the springs 62 against the sides of the horizontal portions 68 thereby locking the compartment. It is obvious that the springs 62 and cooperating lugs 50' and inverted L shaped grooves 52' form a further embodiment of means to space the hole 32 from the dispensing surface 28 and that any type of resilient means and locking means may be used for this purpose.
- It is obvious that I have provided improved means to lock the powder 42 in the compartment 40 when the container is not in use, a feature long desired in vanity cases, that I have provided improved means to feed adjustable predetermined amounts of powder on the dispensing surface 28, that

I have provided improved means to prevent leakage of powder in this type of container and that I have provided locking means to prevent locking of the container except when 5 the compartment is locked.

I employ the word "powder" to include any material in solid form which may be conveniently fed through a spout whether it be actually pulverized or not. I employ the 10 word "regulate" to include contacting of the dispensing surface 28 by the edge of the hole 32 as well as adjustably spacing it therefrom.

I employ the words "dispensing surface" 15 to include only a surface actually contacted by the powder puff or actual dispenser in the process of dispensing powder.

It is understood that my invention is not limited to the specific embodiments shown 20 and that various deviations may be made therefrom without departing from the spirit and scope of the appended claims.

What I claim as new and desire to secure by Letters Patent is:

25 1. In a powder container, the combination of a body member having a rigid dispensing surface thereon adapted to be contacted by a powder puff in the dispensing operation and a cover member therefor having an 30 opening therein over said dispensing surface, said members being shaped to form a powder compartment between them exterior of said opening and being adjustable relative to each other to regulate the amount of 35 powder fed to said dispensing surface between said opening and body member.

2. In a powder container, the combination of a body member having a rigid dispensing surface thereon adapted to be contacted by a 40 powder puff in the dispensing operation and a cover member therefor having an opening therein over said dispensing surface, said members being shaped to form a powder compartment between them exterior of said opening and means to vary the distance between them exterior of said opening and means to vary the distance between 45 said opening and dispensing surface whereby on engagement thereof with each other the powder may be locked within the compartment, on increasing thereof the amount of powder fed to said dispensing surface may be regulated and on separation thereof powder may be inserted in said compartment.

50 3. In a powder container, the combination of a body member having a rigid dispensing surface thereon adapted to be contacted by a powder puff in a dispensing operation and an upwardly projecting ridge surrounding said surface, a cover member therefor having an opening therein overlying said dispensing surface, said members forming thereby a powder compartment between them exterior of said opening and means to

vary the distance between said opening and dispensing surface whereby on engagement of the edge of said opening against said ridge the powder may be locked within said compartment and on increasing the distance between said opening and dispensing surface the amount of powder fed to said dispensing surface may be regulated.

4. In a powder container, the combination of a body member having a cylindrical pocket and a rigid dispensing surface therein adapted to be contacted by a powder puff in the dispensing operation and a cylindrical cover member therefor threadedly engaged with the sides of the cylindrical pocket in said body member and having an opening therein over said dispensing surface, said members being shaped to form a powder compartment between them exterior of said opening and the cover member being revolvable on said body member to regulate the amount of powder fed to said dispensing surface.

5. In a powder container, the combination of a body member having a cylindrical pocket, a rigid dispensing surface therein adapted to be contacted by a powder puff in the dispensing operation and an upwardly projecting ridge surrounding said surface and a cylindrical cover member therefor threadedly engaged with the sides of the cylindrical pocket in said body member and having an opening therein over said dispensing surface, said members being shaped to form a powder compartment exterior of said opening and the cover member being revolvable on said body member to regulate the amount of powder fed to said dispensing surface.

6. In a powder container, the combination of a body member having a rigid dispensing surface adapted to be contacted by a powder puff in the dispensing operation, a cover member therefor having an opening therein adjustable relative to said dispensing surface, and means on said body member adjacent to said dispensing surface adapted to contact the edge of said opening to regulate the amount of powder fed to said dispensing surface.

7. In a vanity case, the combination of a body member having a rigid dispensing surface thereon adapted to be contacted by a powder puff in the dispensing operation and a cover member therefor having a dispensing surface tapering from the sides thereof to an opening therein terminating in an edge adjustable relative to the dispensing surface on the body member, said members forming thereby a powder compartment and being adjustable relative to each other to regulate the amount of powder fed to said dispensing surfaces between the opening and the body member.

8. In a vanity case, the combination of a

body member having a dispensing surface and an upwardly projecting ridge surrounding said surface and a cover member therefor having a dispensing surface tapering 5 from the sides thereof to an opening therein terminating in an edge adjustable relative to said dispensing surface on the body member, said members forming thereby a powder compartment and being adjustable relative 10 to each other to regulate the amount of powder fed to said dispensing surfaces between said opening and body member.

9. In a vanity case, the combination of a body member having a dispensing surface, 15 and an upwardly projecting ridge surrounding said surface, a cover member therefor having a dispensing surface tapering from the sides thereof to an opening therein terminating in an edge adjustable relative to 20 said dispensing surface in the body member, the lower portion of said tapered wall adjacent said ridge being more sharply tapered, said members forming thereby a powder compartment and being adjustable relative 25 to each other to regulate the amount of powder fed to said dispensing surface between the opening and the body member.

10. In a vanity case, the combination of a body member having a cylindrical pocket, 30 and a dispensing surface therein and a cylindrical cover member therefor threadedly engaged with the sides of the cylindrical pocket in said body member and having a dispensing surface tapering from the sides 35 thereof to an opening therein terminating in an edge over said dispensing surface in the body member, said members forming a powder compartment and the cover member being revolvable on said body member 40 to regulate the amount of powder fed to said dispensing surfaces between the opening and body member.

11. In a vanity case, the combination of a body member having a cylindrical pocket, 45 having a dispensing surface therein and an upwardly projecting ridge surrounding said surface and a cylindrical cover member therefor threadedly engaged with the sides of the cylindrical pocket having a dispensing 50 surface tapering from the sides thereof to an opening therein terminating in an edge over said dispensing surface in the body member, said members forming thereby a powder compartment and the cover member being 55 revolvable on the body member to regulate the amount of powder fed to said dispensing surfaces between the opening and body member.

12. In a vanity case, the combination of a body member having a cylindrical pocket, 60 having a dispensing surface therein and an upwardly projecting ridge surrounding said surface and a cylindrical cover member therefor threadedly engaged with the sides 65 of said body member and having a dispens-

ing surface tapering from the sides thereof to an opening therein terminating in an edge over said dispensing surface of the body member, said members forming thereby a powder compartment and the cover member 70 being revolvable on said body member to regulate the amount of powder fed to said dispensing surfaces, the tapered wall of the cover member having a more sharply tapered portion adjacent to said ridge in the body 75 member for powder sealing purposes.

13. In a vanity case, the combination of a cylindrical casing body member having a dispensing surface therein, a cylindrical cover member therefor compactly contained therein having a dispensing surface tapering from the sides thereof to an opening therein terminating in an edge over said dispensing surface in the body member, said members forming thereby a powder compartment, means to 80 threadedly engage the sides of said cover member to the sides of the said body member, an external cover member for said case hinged to said body portion and means to lock said external cover member to said compartment cover member and hence body member when edge of said aperture is in engagement with the powder compartment 85 whereby said case may be locked only when the powder compartment is locked.

14. In a powder container, the combination of a casing body member having a cylindrical pocket having a dispensing surface therein, a cylindrical cover member therefor compactly contained therein having an opening over said dispensing surface, said members being shaped to form a powder compartment between them exterior of said opening, means to threadedly engage the sides of said cover member with the sides of the pocket in said body member, an external cover member for said container hinged to said body portion and means to lock said external cover member to said compartment cover member and hence the body member, 100 when edge of said aperture is in engagement with said dispensing surface in the body member whereby said container may be locked only when said powder compartment is locked.

15. In a vanity case, the combination of a cylindrical casing body member having a dispensing surface, a cylindrical cover member therefor compactly contained therein having a dispensing surface tapering from the sides thereof to an opening therein terminating in an edge over said dispensing surface in the body member, said members forming thereby a powder compartment, means to vary the distance between said opening and body portion, an external cover member for said casing hinged to said body member and latch means on said external cover member adapted to engage complementary latch means on said compartment 110 115 120 125 130

cover member to lock said external cover member to said case only when edge of said aperture is in engagement with the said body member whereby said case may be locked only when said powder compartment is locked.

16. In a powder container, the combination of a casing body member having a cylindrical pocket having a dispensing surface therein, a cylindrical cover member therefor having an opening therein terminating in an edge over said dispensing surface in the body member, said members being shaped to form a powder compartment exterior of said opening, means to vary the distance between said opening and said body member, an external cover member for said container hinged to said body member and latch means on said external cover member adapted to engage complementary latch means on said compartment cover member to lock said external cover member to said container when edge of said aperture is in engagement with said body member whereby said container may be locked only when said powder compartment is locked.

17. In a vanity case, the combination of a cylindrical casing body member having a dispensing surface and threads on the side walls thereof, a cylindrical cover member having side walls of greater height than the side walls of said body portion and having lugs thereon to engage the threads in the side walls of said body portion, a lug protruding radially from the upper portion thereof and a dispensing surface tapering from the sides thereof to an opening therein terminating in an edge over said dispensing surface in the body member, said members forming thereby a powder compartment and being revolvably engaged with each other, an external cover member for said case hinged to said body member having a depression in the side wall thereof adapted to engage said lug in the side wall of said powder compartment cover member when said compartment cover member is revolved to cause the edge of said aperture thereof to engage said dispensing surface in the body member whereby said case may be locked only when said powder compartment is locked.

18. In a vanity case, the combination of a casing body member having a cylindrical pocket having a dispensing surface and threads on the side walls thereof, a cylindrical cover member having side walls of greater height than the side walls of said pocket and having lugs therein to engage the threads in the side walls of said pocket, a lug protruding radially from the upper portion thereof and an opening therein terminating in an edge over said dispensing surface of the body member, said members forming thereby a powder compartment and being revolvably engaged with each other,

an external cover member for said case hinged to said body member having a depression on the side wall thereof adapted to engage said lug in the side wall of said compartment cover member when the compartment cover member is revolved to cause the edge of said aperture thereof to engage said dispensing surface of the body member whereby said case may be locked only when said powder compartment is locked.

19. In a powder container, the combination of a body having a rigid dispensing surface thereon adapted to be contacted by a powder puff in the dispensing operation, a cover member therefor having an opening therein over said dispensing surface, said members being shaped to form a powder compartment between them and means to vary the distance between said opening and dispensing surface.

20. In a powder container, the combination of a body member having a rigid dispensing surface thereon adapted to be contacted by a powder puff in the dispensing operation, a cover member therefor having an opening therein over said dispensing surface, said members being shaped to form a powder compartment between them and a spout leading to the dispensing surface and means to vary the distance between said opening and dispensing surface.

21. In a powder container, the combination of a body member having a cylindrical pocket, a cylindrical revolvable powder dispensing cover member shaped to form with the body member a powder compartment and adapted to dispense powder therefrom on revolution thereof, means to threadedly engage the sides of said cover member with the sides of said pocket, an external cover member hinged to said body member and latch means on said external cover member adapted to engage complementary latch means on said compartment cover member to lock said external cover member to said container only when the compartment cover member is revolved to lock the powder compartment.

22. In a powder container, the combination of a body member having a pocket, a movable powder dispensing cover member for said pocket shaped to form with the body member a powder compartment and adapted to dispense powder on movement thereof, an external cover member hinged to said body member and latch means on said external cover member adapted to engage complementary latch means on said movable compartment cover member to lock said external cover member to said container only when the compartment cover member is moved to lock the powder compartment.

23. In a powder container, the combination of a casing body member having a cylindrical pocket having lugs in the side

- walls thereof, a cylindrical cover member for said pocket having side walls having threads therein to engage the lugs in the side walls of said pocket, a lug protruding 5 radially from the upper portion of the side walls thereof and means to dispense powder therefrom, said members being shaped to form a powder compartment and being revolvably engaged with each other, an external member for said container hinged to 10 said body member having a depression in the side walls thereof adapted to engage said lug on the upper portion of the side wall of the said compartment cover member when said compartment cover member is 15 revolved to lock the powder compartment whereby said container may be locked only when said powder compartment is locked.
24. In a powder container, the combination of a body member having a pocket, an external cover member hinged to said body member having a latch portion opposite said hinge, a cover member for said pocket secured within said body portion and capable 25 of relative movement therein having a cooperating latch portion thereon adapted to engage with said latch portion on said external cover member when said latch portions are brought into alignment and a radially 30 projecting bead for gripping and powder sealing purposes on the upper portion of the side wall thereof above said pocket, a portion of the bead being omitted adjacent to the hinge.
35. 25. In a powder container, the combination of a body member having a cylindrical pocket and an external cover member hinged to said body member having a latch portion opposite said hinge and a cylindrical powder dispensing cover member revolvably 40 threadedly engaged with the sides of said pocket having a cooperating latch portion thereon adapted to engage with said latch portion on said external cover member when 45 said portions are brought into alignment on relative revolution of said members and a radially projecting bead for gripping and powder sealing purposes on the upper portion of the side wall thereof above said pocket, a portion of the bead being omitted adjacent to the hinge.
50. 26. In a powder container, the combination of a body member having a cylindrical pocket and a cylindrical cover member for 55 said pocket threadedly revolvably engaged with each other by lugs projecting from one member fitting into grooves in the other member angularly disposed relative to the base of the body member and grooves ex- 60 tending vertically from said grooves to permit separation of said members when relatively revolved to a predetermined position, said vertically extending grooves having dam portions of lesser depth therein whereby said 65 members may be freely revolved in said an-
- gularly disposed grooves and may be separated on exertion of a comparatively greater force to raise said lugs over said dam portions.
27. In a powder container, the combination of a body member having a cylindrical pocket having radially inwardly projecting lugs in the side wall thereof and a cylindrical cover member for said pocket having radially inwardly projecting grooves in the side wall thereof angularly disposed relative to the base of the body member to receive the lugs of said body member and grooves extending downwardly from said grooves to permit separation of said members when relatively revolved to a predetermined position, said downwardly extending grooves having dam portions of lesser depth therein whereby said members may be freely revolved in said angularly disposed grooves and may be separated on the exertion of a greater force to raise said lugs over said dam portions.
28. In a powder container, the combination of a body member having a cylindrical pocket having a plurality of lugs projecting radially inwardly of the sides thereof, an external cover member hinged to said body member having a latch portion opposite said hinge, a cylindrical compartment cover member for said pocket adapted to dispense powder on revolution thereof having a cooperating latch portion on the upper portion of the side wall thereof adapted to engage with said latch portion on said external cover member when said latch portions are brought into alignment, a plurality of grooves on the side wall thereof angularly disposed relative to the base of the body member to receive the lugs of said body member and grooves extending downwardly from said grooves to permit separation of said compartment cover and body members when relatively revolved to a predetermined position and a radially projecting bead for gripping and powder sealing purposes on the upper portion of the side wall thereof adapted to engage the upper edge of the side wall of the body portion to seal the powder, a portion of said bead being omitted between two of said grooves adjacent to said hinge to provide an indication whereby the proper lugs may be inserted in the proper grooves to bring the latch portion on the powder compartment cover member into alignment with the latch portion on said external cover member to permit locking of the external cover member to the container only when the compartment cover member is revolved to a predetermined position.
29. In a vanity case, the combination of a body member having a cylindrical pocket having a plurality of lugs projecting radially inwardly from the sides thereof, a dispensing surface therein and an upwardly projecting ridge surrounding said surface,

an external cover member hinged to said body member having a latch portion opposite said hinge, a cylindrical compartment cover member for said pocket having a dispensing surface tapering from the sides thereof to an opening therein terminating in an edge adjustable relative to said dispensing surface and ridge in the body member, a cooperating latch portion on the upper portion of the side wall thereof adapted to engage said latch portion on the external cover member when said latch portions are brought into alignment, a plurality of grooves in the side walls thereof angularly disposed relative to the dispensing surface of the body member to receive the lugs on said body member and grooves extending downwardly from said grooves to permit separation of said compartment cover and body members when relatively revolved to a predetermined position, said downwardly projecting grooves having dam portions of

lesser depth therein and a radially projecting bead for gripping and powder sealing purposes on the upper portion of the side wall thereof adapted to engage the upper side of the pocket of the body portion to seal said powder within said compartment when said compartment cover is lowered to cause the edge of said opening to engage the dispensing surface of the body member to seal the compartment, a portion of said bead being omitted between two of said grooves adjacent to said hinge to provide an indication whereby the proper lugs may be inserted in the proper grooves to bring the latch portion on the compartment cover member in alignment with the latch portion on said external cover member to permit locking of the external cover member to the case only when the compartment cover member is revolved to lock the powder compartment. 25 30 35 40

In testimony whereof I affix my signature.
JACOB HEILBRON.
